UNITED STATES PATENT OFFICE.

MILES B. McCLUNG, OF McCLUNGS, WEST VIRGINIA.

PICTURE-HANGER.

1,304,337.

Specification of Letters Patent. Patented May 20, 1919.

Application filed July 20, 1918. Serial No. 245,862.

To all whom it may concern:

Be it known that I, MILES B. McCLUNG, a citizen of the United States, residing at Mc-Clungs, in the county of Greenbrier and State of West Virginia, have invented new and useful Improvements in Picture-Hangers, of which the following is a specification.

This invention relates to picture hangers and it consists in the novel features herein-10 after described and claimed.

An object of the invention is to provide a hanger of simple and durable structure adapted to securely retain a picture in order that the same may be suspended from a securing device applied to a wall or similar support.

15 The parts of the hanger are so arranged that the picture may be readily detached from the same without removing the hanger from the wall or support.

20 With these objects in view the hanger comprises a body portion of wire having downwardly and outwardly disposed leg portions with upstanding extremities adapted to receive the lower portion of a picture frame. A wire member is interwoven or

25 twisted with the upper portion of the body and is provided with outstanding arm portions which in turn are provided at their outer ends with inwardly disposed extremities adapted to engage around the upper portion of the sides of the frame of a picture. The lower portions of the legs are connected together by a cross rod or bar whereby the legs are prevented from spreading under

30 the weight of the picture. Inasmuch as the arm portion is applied to the body portion the material at the upper part of the hanger is doubled and this doubled material is twisted and is provided at its upper portion 40 with a loop adapted to receive a hook or other securing device whereby the hanger may be connected with the wall or support.

In the accompanying drawings:—

Figure 1 is a front elevation of a picture frame indicating the hanger applied.

Fig. 2 is a perspective view of one form of the hanger.

Fig. 3 is a detailed perspective view of a portion thereof.

50 Fig. 4 is an edge view of the upper portion thereof.

Fig. 5 is a perspective view of a support for the hanger.

Fig. 6 is a front view of a modified form of the hanger. 55

Fig. 7 is a similar view showing the parts thereof folded.

Fig. 8 is a side view of a modified form of support for the hanger.

The picture hanger includes a body wire 60 or rod 1 having its end portions disposed at an acute angle with relation to each other and constituting legs 2. The legs 2 are provided at their lower ends with upwardly and forwardly disposed extremities 3 upon 65 which the lower portion of a picture frame may rest. The legs 2 are provided at points between their ends with loops 4 and the end portions of a rod 5 are engaged through the said loops whereby the lower portions of the 70 legs 2 are prevented from spreading with relation to each other when the legs are subjected to the weight of the picture. The body 1 is provided at the apex of the angle formed by the legs 2 with an eye 6 through 75 which a hook or securing device may pass.

A wire or rod 7 constitutes a shoulder portion and is applied to the upper part of the body portion by twisting the said shoulder portion around the body portion. The said 80 shoulder portion 7 is provided with an eye 8 which registers with the eye 6 and the supporting device may therefore pass through both of the eyes 6 and 8. The shoulder portion 7 is provided with outstanding arms 9 85 adapted to extend along the back of a picture which is applied to the hanger and the arms 9 are provided at their outer ends with forwardly and inwardly disposed extremities 10 adapted to engage around the edges 90 of the side pieces of the frame of the picture.

The supporting device 11 is preferably permanently connected by the hanger having its eye extending through the eyes 6 and 8 and the said securing device may be driven 95 or screwed into the wall or support.

When the hanger is applied to a support a picture may be readily inserted therein and supported thereby by placing the lower portion of the frame upon the extremities 3 and 100 then springing the extremities 10 around the upper portions of the sides of the frame. To remove the picture the operation described is reversed.

From the foregoing description taken in 105 conjunction with the accompanying draw-

ings it will be seen that a picture hanger of simple and durable structure is provided and that the same may be conveniently used for securely retaining a picture in position upon 5 its support.

In the form of the invention as shown in Figs. 6 and 7 the same general arrangement of the parts as shown in Fig. 2 is observed. The legs 2 are composed of sections hingedly 10 connected together as at 12 and the arms 9 are composed of sections hinged together as at 13. Therefore the parts may be folded as shown in Fig. 7 for storage or transportation. The supporting device 11 as shown 15 in Fig. 8 is provided with a hook 14 which may be engaged through the eyes 6 and 8 to support the hanger.

Copies of this patent may be obtained for five cents each, by addressing the "Commissioner of Patents, Washington, D. C."

Having described the invention what is claimed is:

A picture hanger comprising a body having divergent leg portions provided with parallel outstanding extremities, a rod connecting the intermediate portions of the legs together, a shoulder portion twisted upon the upper part of the leg portions and having an eye, the body portion having an eye at the union of the legs which registers with the eye of the shoulder portion, said shoulder portion having alined outstanding arms provided with laterally disposed extremities 20 25 30 inwardly directed.

In testimony whereof I affix my signature.

MILES B. McCLUNG.
